CLAIM

The ornamental design for an eyelash conditioner container, as shown and described.

DESCRIPTION

FIG. 1 is a front perspective view of an eyelash conditioner container, showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view thereof;

FIG. 7 is an enlarged bottom plan view thereof; and,

FIG. 8 is an exploded perspective view showing the eyelash conditioner container components separated from one another, for clarity of illustration.

(Continued)

The broken lines in the drawings illustrate the portions of the eyelash conditioner container, which form no part of the claimed design.

1 Claim, 8 Drawing Sheets
